(57) **CLAIM**

The ornamental design of a package for sewing machine needles, as shown and described.

DESCRIPTION

FIG. 1 is a front view of a package for sewing machine needles according to the present invention;

FIG. 2 is a back view thereof;

FIG. 3 is a right side view thereof, the left side view being a mirror image thereof;

FIG. 4 is a top view thereof;

FIG. 5 is a bottom view thereof;

FIG. 6 is a perspective view thereof; and,

FIG. 7 is a perspective view thereof with the upper part of the component opened by sliding the wrapper film downward.
